UNITED STATES PATENT OFFICE.

JULIUS B. WANTZ, OF OAK PARK, ILLINOIS, ASSIGNOR TO VICTOR X-RAY CORPORATION, OF CHICAGO, ILLINOIS, A CORPORATION OF NEW YORK.

DESIGN FOR AN ELECTROTHERAPEUTIC-MACHINE CASING.

Application filed August 24, 1926. Serial No. 18,839. Term of patent 14 years.

To all whom it may concern:

Be it known that I, JULIUS B. WANTZ, a citizen of the United States, residing at 324 North Harvey Avenue, Oak Park, county of Cook, and State of Illinois, have invented a new, original, and ornamental Design for Electrotherapeutic-Machine Casing, of which the following is a specification, refer-

ence being had to the accompanying drawing, forming part thereof.

The figure is a front elevation of a casing embodying the invention.

I claim:

The ornamental design for electrotherapeutic machine casing, as shown.

JULIUS B. WANTZ.
